UNITED STATES PATENT OFFICE.

HOWARD M. BARBER, OF STONINGTON, CONNECTICUT, ASSIGNEE TO C. B. COTTRELL & SONS COMPANY, OF NEW YORK, N. Y., A CORPORATION OF DELAWARE.

DELIVERY MECHANISM FOR SHEET-FEED ROTARY PRESSES.

1,223,023.

Specification of Letters Patent. Patented Apr. 17, 1917.

Application filed July 31, 1915. Serial No. 42,930.

To all whom it may concern:

Be it known that I, HOWARD M. BARBER, a citizen of the United States, and resident of Stonington, in the county of New London 5 and State of Connecticut, have invented a new and useful Improvement in Delivery Mechanisms for Sheet-Feed Rotary Presses, of which the following is a specification.

The object of this invention is to provide 10 a delivery mechanism which will successfully deliver the printed sheets whether printed with continuous margins or with staggered margins without smutting or smearing the printed matter on said sheets.

15 The invention more particularly includes a delivery cylinder provided with marginal risers which can be so located on the cylinder as to support the printed sheet by its margins whether continuous or staggered and 20 thus space the printed matter from the surface of the cylinder.

My invention also includes movable guides for directing the advance edge of the printed sheet into position to be engaged by the delivery carrier grippers together with a slip sheet, the movable guide being moved away 25 from the printed face of the sheet to prevent the guide from smutting or smearing the same.

30 A practical embodiment of my invention is represented in the accompanying drawings, in which—

Figure 1 represents in side elevation so much of a sheet feed rotary printing press 35 as includes my invention.

Fig. 2 is a detail section showing the delivery cylinder in end elevation.

Fig. 3 is a horizontal section through the machine,

40 Fig. 4 is a vertical section through the machine taken from front to rear.

Fig. 5 is an enlarged detail section through one of the marginal risers, showing the means for securing the same to the delivery 45 cylinder.

Fig. 6 is a detail view showing the movable guide in position for directing the advance edge of the printed sheet together with the slip sheet into the delivery carrier 50 grippers.

Fig. 7 is a similar view with the movable guide raised to lift it from the printed portion of the sheet, and

55 Fig. 8 is a plan view of the sheet showing certain of its longitudinal margins staggered

with respect to the other longitudinal margins.

The impression cylinder is denoted by 1 and its plate cylinders by 2. These impression and plate cylinders and the means, such 60 as the cylinder 3, for feeding sheets thereto may be of any well known and approved construction and no specific description thereof will be given.

The sheet delivery mechanism for the 65 press includes a rotary delivery cylinder 4 mounted on a suitable shaft 5 and provided with a set of grippers 6, which grippers are arranged to take the head of the printed sheet from the impression cylinder 1 with 70 the printed side of the sheet toward the delivery cylinder and to deliver the sheet printed side up between the fixed guide 7 and movable guide 8. The slip sheets are arranged to be fed between the fixed guides 75 7 and 9.

An endless carrier 10 is provided at intervals with grippers 11 arranged to take the heads of the printed sheet and slip sheet at 80 the ends of the guides 7, 8 and 9, and convey the sheets to a point over the delivery table 12 where the grippers are opened by a cam 13 for releasing the sheets and permitting them to drop onto the said table 12. A cam 14 is provided for opening the grippers 11 85 to receive the sheets. A suitable retarding mechanism 15 for the sheets is employed, which mechanism will not be described or claimed herein as it forms a part of the subject-matter of my copending application 90 filed on the 21st day of September 1915, its serial number being 51,787.

The sheet illustrated in Fig. 8 is shown as provided with two continuous margins 95 16, 17, lengthwise of the travel of the sheet and also five intermediate shorter margins 18, 19, 20, 21, 22, lengthwise of the travel of the sheet, arranged in staggered order intermediate the side margins 16, 17. It frequently occurs in printing that the margins 100 lengthwise of the travel of the sheet are not continuous from the head to the tail of the sheet, and it is to provide means for successfully passing a sheet of this character around the delivery cylinder without smutting the freshly printed face of the sheet 105 that one phase of my invention is directed.

To accomplish this result the delivery cylinder 4 is provided with a plurality of marginal risers which are adjustable both later- 110

ally and circumferentially on the cylinder and which correspond in length and position to the margins on the sheets to be delivered. In the present instance the marginal risers 23, 24, are arranged to engage the continuous margins 16, 17, of the sheet illustrated, while the marginal risers 25, 26, 27, 28, 29 are arranged to engage the shorter margins 18, 19, 20, 21, 22, respectively, of the sheet; the sheet thus being supported lengthwise thereof by its continuous and staggered margins as it passes around the cylinder.

The means which I have shown for holding the marginal risers in position around the surface of the cylinder includes clamping plates 30, engaging the risers, adjustable shoes 31, spirally arranged undercut grooves 32 in the face of the cylinder and clamping screws 33 engaging the plates and shoes.

This arrangement, it will be seen, will permit the very rapid positioning of the marginal risers on the cylinder and will also permit the rapid insertion of risers of the desired lengths and in the desired number to correspond with sheets having many different arrangements of the margins whether continuous or staggered.

Another feature of my invention is the movable guide 8 arranged over the stationary guide 7, having its delivery end arranged to depress the head of the printed sheet to bring it into proximity to the head of the slip sheet for insuring the transfer of the two sheets to the delivery carrier 11. The delivery end of the movable guide 8 is arranged to be immediately removed from its engagement with the freshly printed face of the sheet as soon as the printed sheet and slip sheet are engaged by the grippers 11, so that the said freshly printed face of the sheet will not be smutted by the dragging of the guide over said face. The means which I have shown for moving this guide comprises a cam 34 on the shaft 5 of the delivery cylinder, which cam engages a stud or roller 35 fast to a bar 36 connected to an arm 37 fast to a rock bar 38, to which rock bar the movable guide 8 is also fixed. This cam 34 may be adjusted to properly time the movement of the guide 8 with respect to the grippers 11 of the delivery carrier.

I provide means for maintaining control of the sheets on the delivery cylinder after the heads of the sheets are released by the grippers 6, said means in the present instance, comprising a series of friction rollers 39 carried by spring-actuated rock levers 40 pivoted at 41 to arms 42 adjustable laterally along the cross bar 43 and held in the desired adjustments by the set screws 44. The desired amount of pressure which these rollers 39 exert upon the marginal risers is adjusted by means of springs 45. It is to be understood that there may be one of these

rollers 39 for each of the marginal risers and also that these rollers may be prevented from pressing against the face of the cylinder when they ride off the ends of the marginal risers. This latter result may be accomplished by suitable adjustable stops 46 carried by the arms 42 and arranged to be engaged by tail pieces 47 on the rock levers 40. It is intended that these rollers 39 should coact with the marginal risers to maintain control of the printed sheets until the heads of the sheets are engaged by the delivery carrier grippers 11.

It is evident that the driving connections between the several parts may be arranged to drive the parts at the proper relative speeds and as such driving mechanism may be of any well known or approved form, no specific description of the same will be given herein.

It is also obvious that when I refer to the element 4 as a delivery cylinder, I wish to include by such term a reel or other equivalent means capable of passing the sheets from the impression cylinder to the desired point, and that also by the term "grippers" I intend to include any equivalent means for engaging the sheets to convey them through the prescribed paths.

What I claim is:

1. A sheet delivery mechanism for printing presses including a delivery cylinder, risers thereon for engaging the margins of the sheet whether continuous or staggered for passing the sheet around the cylinder without smutting the freshly printed face of the sheet and means coacting with the risers for controlling the movement of the sheet.

2. A sheet delivery mechanism for printing presses including a delivery cylinder, risers thereon for engaging the margins of the sheet whether continuous or staggered for passing the sheet around the cylinder without smutting the freshly printed face of the sheet, and rollers coacting with the risers for controlling the movement of the sheet.

3. A sheet delivery mechanism for printing presses including a delivery cylinder, risers adjustable thereon to bring them into correspondence with the margins of the sheet whether continuous or staggered for passing the sheet around the cylinder without smutting the freshly printed face of the sheet and means coacting with the risers for controlling the movement of the sheet.

4. A sheet delivery mechanism for printing presses including a delivery cylinder, risers adjustable thereon to bring them into correspondence with the margins of the sheet whether continuous or staggered for passing the sheet around the cylinder without smutting the freshly printed face of the sheet, and rollers coacting with the risers for controlling the movement of the sheet.

5. A sheet delivery mechanism for print-

ing presses including a sheet delivery cylinder having grippers for engaging the head of the sheet and risers on the cylinder for engaging the margins of the sheet whether continuous or staggered for passing the sheet around the cylinder without smutting the freshly printed face of the sheet.

6. A sheet delivery mechanism for printing presses including a sheet delivery cylinder having grippers for engaging the head of the sheet, risers on the cylinder for engaging the margins of the sheet whether continuous or staggered for passing the sheet around the cylinder without smutting the freshly printed face of the sheet, and rollers coacting with the risers to maintain control of the sheet after it has been released by the grippers.

7. A sheet delivery mechanism for printing presses including a sheet delivery cylinder having grippers for engaging the head of the sheet and risers adjustable on the cylinder to bring them into correspondence with the margins of the sheet whether continuous or staggered for passing the sheet around the cylinder without smutting the freshly printed face of the sheet.

8. A sheet delivery mechanism for printing presses including a sheet delivery cylinder having grippers for engaging the head of the sheet, risers adjustable on the cylinder to bring them into correspondence with the margins of the sheet whether continuous or staggered for passing the sheet around the cylinder without smutting the freshly printed face of the sheet, and rollers coacting with the risers to maintain control of the sheet after it has been released by the grippers.

40 9. A sheet delivery mechanism for printing presses including a sheet delivery cylinder and risers thereon corresponding in position and length with the margins of the sheet whether continuous or staggered for passing the sheet around the cylinder without smutting the freshly printed face of the sheet.

50 10. A sheet delivery mechanism for printing presses including a sheet delivery cylinder, risers thereon corresponding in position and length with the margins of the sheet whether continuous or staggered for passing the sheet around the cylinder without smutting the freshly printed face of the sheet, and rollers coacting with the risers for controlling the movement of the sheet.

55 11. A sheet delivery mechanism for printing presses including a sheet delivery cylinder and risers adjustable thereon to bring them into correspondence with the margins of the sheet whether continuous or staggered for passing the sheet around the cylinder without smutting the freshly printed face of the sheet.

65 12. A sheet delivery mechanism for print-

ing presses including a sheet delivery cylinder, risers adjustable thereon to bring them into correspondence with the margins of the sheet whether continuous or staggered for passing the sheet around the cylinder without smutting the freshly printed face of the sheet, and rollers coacting with the risers for controlling the movement of the sheet.

13. A sheet delivery mechanism for printing presses including a sheet delivery cylinder and risers adjustable both laterally and circumferentially thereon to bring them into correspondence with the margins of the sheet whether continuous or staggered for passing the sheet around the cylinder without smutting the freshly printed face of the sheet and means coacting with the risers for controlling the movement of the sheet.

14. A sheet delivery mechanism for printing presses including a sheet delivery cylinder, risers adjustable both laterally and circumferentially thereon to bring them into correspondence with the margins of the sheet whether continuous or staggered for passing the sheet around the cylinder without smutting the freshly printed face of the sheet, and rollers coacting with the risers for controlling the movement of the sheet.

15. A sheet delivery mechanism for printing presses including a sheet delivery cylinder having grippers for engaging the head of the sheet and risers on the cylinder corresponding in position and length with the margins of the sheet whether continuous or staggered for passing the sheet around the cylinder without smutting the freshly printed face of the sheet and means coacting with the risers to maintain the control of the sheet after it has been released by the grippers.

16. A sheet delivery mechanism for printing presses including a sheet delivery cylinder having grippers for engaging the head of the sheet, risers on the cylinder corresponding in position and length with the margins of the sheet whether continuous or staggered for passing the sheet around the cylinder without smutting the freshly printed face of the sheet and rollers coacting with the risers to maintain the control of the sheet after it has been released by the grippers.

17. A sheet delivery mechanism for printing presses including a sheet delivery cylinder having grippers for engaging the head of the sheet and risers adjustable on the cylinder to bring them into correspondence with the margins of the sheet whether continuous or staggered for passing the sheet around the cylinder without smutting the freshly printed face of the sheet, and means coacting with the risers to maintain the control of the sheet after it has been released by the grippers.

18. A sheet delivery mechanism for print-

- ing presses including a sheet delivery cylinder having grippers for engaging the head of the sheet, risers adjustable on the cylinder to bring them into correspondence with the 5 margins of the sheet whether continuous or staggered for passing the sheet around the cylinder without smutting the freshly printed face of the sheet, and rollers coacting with the risers to maintain the control 10 of the sheet after it has been released by the grippers.
19. A sheet delivery mechanism for printing presses including a sheet delivery cylinder having grippers for engaging the head of the sheet and risers adjustable both laterally and circumferentially on the cylinder to bring the risers into correspondence with the margins of the sheet whether continuous or staggered for passing the sheet 15 around the cylinder without smutting the freshly printed face of the sheet, and means coacting with the risers to maintain the control of the sheet after it has been released by the grippers.
20. A sheet delivery mechanism for printing presses including a sheet delivery cylinder having grippers for engaging the head of the sheet, risers adjustable, both laterally and circumferentially on the cylinder to bring the risers into correspondence with the margins of the sheet whether continuous or staggered for passing the sheet around the cylinder without smutting the freshly printed face of the sheet, and rollers coacting 25 with the risers to maintain the control of the sheet after it has been released by the grippers.
21. A sheet delivery mechanism for printing presses including a sheet delivery cylinder having spirally arranged grooves, risers adjustable laterally and circumferentially to bring them into correspondence with the margins of the sheet whether continuous or staggered for passing the sheet around the cylinder without smutting the freshly printed face of the sheet, and devices engaging the 30 said grooves and risers for holding the risers in their adjusted positions.
22. A sheet delivery mechanism for printing presses including a sheet delivery cylinder having spirally arranged grooves, risers adjustable laterally and circumferentially to bring them into correspondence with the margins of the sheet whether continuous or staggered for passing the sheet around the cylinder without smutting the freshly printed face of the sheet, devices engaging the 35 said grooves and risers for holding the risers in their adjusted positions, and rollers coacting with the risers for controlling the movement of the sheet.
23. A sheet delivery mechanism for print- 40
- ing presses including a sheet delivery cylinder having grippers for engaging the head of the sheet and also having spirally arranged grooves, risers adjustable laterally and circumferentially to bring them into correspondence with the margins of the sheet whether continuous or staggered for passing the sheet around the cylinder without smutting the freshly printed face of the sheet and devices engaging the grooves and risers for holding the risers in their adjusted 45 positions.
24. A sheet delivery mechanism for printing presses including a sheet delivery cylinder having grippers for engaging the head of the sheet and also having spirally arranged grooves, risers adjustable laterally and circumferentially to bring them into 50 correspondence with the margins of the sheet whether continuous or staggered for passing the sheet around the cylinder without smutting the freshly printed face of the sheet, devices engaging the grooves and 55 risers for holding the risers in their adjusted positions, and rollers coacting with the risers to maintain control of the sheet after it has been released by the grippers.
25. A sheet delivery mechanism for printing presses including a traveling endless delivery carrier having grippers, guides for directing printed and slip sheets to the grippers and means for moving the delivery end of one of the guides in one direction to 60 direct the head of the printed sheet into the grippers and in the other direction to prevent the smutting of the sheet by said guide.
26. A sheet delivery mechanism for printing presses including delivery carrier grippers, a delivery cylinder and its grippers, a guide for directing the sheet from the cylinder grippers to the delivery carrier grippers and additional means coacting with said cylinder for maintaining control of the sheet 65 on the delivery cylinder until the head of the sheet has been taken by the delivery carrier grippers.
27. A sheet delivery mechanism for printing presses including delivery carrier grippers, a delivery cylinder and its grippers, a guide for directing the sheet from the cylinder grippers to the delivery carrier grippers, and additional means coacting with said cylinder for maintaining control of the sheet 70 on the delivery cylinder until the head of the sheet has been taken by the delivery carrier grippers, said additional means including marginal risers on the cylinder and pressure rollers coacting therewith.
- In testimony, that I claim the foregoing as my invention, I have signed my name this twenty-third day of July, 1915.
- HOWARD M. BARBER.
